GRINDING MACHINE

John I. Garside, West Boylston, Mass., assignor to
 Norton Company, Worcester, Mass., a corpora-
 tion of Massachusetts

Application February 25, 1943, Serial No. 477,043

1 Claim. (Cl. 51—105)

The invention relates to grinding machines and more particularly to a cylindrical type grinding machine adapted for successively grinding a plurality of shouldered portions on a work piece.

One object of the invention is to provide an improved hydraulically operated shoulder type grinding machine for precisely grinding a plurality of spaced shoulders on a work piece. Another object of the invention is to provide a multiple stop feeding mechanism for precisely feeding the grinding wheel for grinding a plurality of spaced shoulders of different diameters. Another object of the invention is to provide a table locating index mechanism and an index control for the grinding wheel feeding stops to facilitate positioning the feed stops relative to the portion of the work piece to be ground. Another object of the invention is to provide a manually operable index mechanism having a plurality of feed control stops precisely to locate said stops in an operative position for grinding predetermined shouldered portions on a work piece. Other objects will be in part obvious or in part pointed out hereinafter.

The invention accordingly consists in features of construction, combinations of elements, and arrangements of parts, as will be exemplified in the structure to be hereinafter described, and the scope of the application of which will be indicated in the following claim.

In the accompanying drawings in which is shown one of various possible embodiments of the mechanical features of this invention,

Fig. 1 is a front elevation of an improved grinding machine embodying this invention;

Fig. 2 is a fragmentary piping and wiring diagram, showing the hydraulically operated system for controlling the feeding movement of the grinding wheel together with the electrically operated control mechanism therefor;

Fig. 3 is a fragmentary vertical sectional view on an enlarged scale, taken approximately on the line 3—3 of Fig. 1, showing the feed stop control lever and associated parts;

Fig. 4 is a fragmentary elevation partly in section, on an enlarged scale showing the relationship between the feed stops or gauge blocks and the hydraulically operated feed mechanism;

Fig. 5 is a fragmentary front elevation on an enlarged scale, of the control lever and the feed stop and the interconnections therebetween; and

Fig. 6 is a fragmentary plan view of the parts shown in Fig. 5.

A grinding machine has been illustrated in

the drawings comprising a base 10 which supports a longitudinally traversable work supporting table 11. The work supporting table 11 is arranged to slide longitudinally on a flat way 12 and a V-way (not shown) formed on the upper surface of the base 10. The work supporting table 11 serves as a support for a headstock 13 and a footstock 14 which are provided with work supporting centers 15 and 16 respectively. The work supporting centers 15 and 16 serve rotatably to support a work piece 17 having a plurality of shouldered portions 17a, 17b, 17c, 17d, 17e, 17f, and 17g, to be ground.

The base 10 also serves as a support for a transversely movable wheel slide 20 which rotatably supports a wheel spindle 21 in suitable bearings (not shown). A grinding wheel 22 is mounted on one end of the wheel spindle 21. The grinding wheel 22 is preferably driven by an electric motor 23 which is mounted on the upper surface of the wheel slide 20. A driving pulley 24 is mounted on the outer end of a motor shaft 25. The driving pulley 24 is preferably a multi-V-groove pulley which is connected by multi-V belts 26 with a multiple V groove pulley 27 mounted on the right-hand end of the wheel spindle 21 (Fig. 1). The wheel slide 20 is arranged to slide transversely relative to the base 10 on the usual well known flat and V ways (not shown) which is a common and well known practice in the grinding art.

The work supporting table 11 may be traversed longitudinally by means of a manually operable traversing mechanism comprising a manually operable traverse wheel 30 which is supported on the outer end of a shaft 31. The inner end of the shaft 31 is provided with a gear 32 which meshes with a gear 33 mounted on a rotatable shaft 34. The shaft 34 also carries a gear 35 which meshes with a rack bar 36 depending from the underside of the work supporting table 11. It will be readily apparent from the foregoing disclosure that rotation of the hand wheel 30 will be imparted through the gear mechanism just described to traverse the table 11 longitudinally in either direction, the direction of movement of the table 11 being determined by the direction of rotation of the traverse wheel 30.

If desired, the table 11 may be traversed or reciprocated longitudinally by a hydraulically operated mechanism comprising a hydraulic cylinder 40 which is supported on the underside of the table 11. The cylinder 40 contains a pair of spaced pistons 41 and 42 which are connected by hollow piston rods 43 and 44 respec-

tively with hollow brackets 45 and 46 respectively which are in turn fixedly mounted on the opposite ends of the base 10.

A reversing lever 47 is supported on the front end of a rock shaft 48 which is connected to actuate a control valve (not shown) located within the machine base 10. A manually operable stop and start lever 49 is also mounted on the front of the machine base 10 and is arranged to actuate a stop and start valve (not shown) to stop and start the traversing or reciprocating movement of the table 11. The details of this hydraulic traversing or reciprocating mechanism have not been illustrated in the present case since this mechanism is substantially identical with that shown in the prior United States patent to Wallace H. Wood, No. 2,071,677, dated February 23, 1937, to which reference may be had for details of disclosure not contained herein. A pair of table reversing dogs 50 and 51 are adjustably supported by a T-slot 52 formed in the front edge of the work supporting table 11.

Wheel feeding mechanism

A wheel feeding mechanism is provided for controlling the infeeding movement of the grinding wheel 22. The wheel slide 20 is provided with a depending half nut 55 which meshes with a rotatable cross feed screw 56. The feed screw 56 is rotatably supported at one end by a bearing 57 which is fixedly supported in relation to the base 10. The other end of the feed screw 56 is rotatably journaled in a slidably mounted bearing unit 58 which is slidably keyed within a cylindrically shaped aperture formed within the base 10 of the machine. The feed screw 56 may be rotated manually for adjusting the position of the grinding wheel slide 20 in setting up the machine by means of a manually operable feeding mechanism to be herein-after described.

A reduced forward end portion 60 of the feed screw 56 is slidably keyed within a rotatable sleeve 61 which is fixedly connected to a shaft 62 which supports a gear 63. The gear 63 meshes with a gear 64 mounted on the inner end of a shaft 65 the other end of which supports a manually operable feed wheel 66. By rotation of the feed wheel 66, the feed screw 56 may be rotated in either direction to cause the grinding wheel 22 and its supporting slide 20 to move either toward or from the work piece 17.

A reduced forward end portion 60 of the feed screw 56 is slidably keyed within a rotatable sleeve 61 which is fixedly connected to a shaft 62 which supports a gear 63. The gear 63 meshes with a gear 64 mounted on the inner end of a shaft 65, the other end of which supports a manually operable feed wheel 66. By rotation of the feed wheel 66, the feed screw 56 may be rotated in either direction to cause the grinding wheel 22 and its supporting slide 20 to move either toward or from the work piece 17. A stop pawl 67 is pivotally mounted on the front of the machine base 10 and is arranged in the path of a stop abutment 68 to facilitate precisely stopping the infeeding movement of the grinding wheel 22.

In order that the wheel slide 20 may be rapidly moved toward the work supporting table 11 to grind a work piece 17 by the plunge-cut method, the feed screw 56 is connected to a piston rod 70. A fluid pressure cylinder 71 is mounted within the base 10 of the machine and contains a slidably mounted piston 72 which is

connected with or formed integral with piston rod 70. As illustrated in Fig. 2, the other end of the piston rod 70 is fixedly connected to the slidably mounted bearing unit 58 so that when fluid under pressure is admitted to either end chamber of the cylinder 71, the endwise movement of the piston rod 70 will be transmitted to produce an axial endwise movement of the feed screw 56 which in turn transmits this motion to produce a transverse feeding movement of the grinding wheel slide 20 and the rotatable grinding wheel 22. A motor driven fluid pressure pump 74 is arranged to pump fluid through a pipe 75 from a reservoir 76 which is located within the base 10 of the machine. The pump 74 forces fluid under pressure through a pipe 77 to a feed control valve 78. The feed control valve 78 is preferably a piston type valve comprising a valve stem 79 having formed integrally therewith a plurality of valve pistons. In the position of the valve 78 (Fig. 2) fluid under pressure passing through the pipe 77 passes through a passage 80 and a cylinder chamber 81 to move the piston 72 together with the wheel slide 20 and the grinding wheel 22 to a rearward or inoperative position. During the passage of fluid under pressure into the cylinder chamber 81, fluid is exhausted from a cylinder chamber 82 through a passage 83 and out through an exhaust pipe 84 into the reservoir 76.

Similarly when the valve stem 79 is shifted toward the left (Fig. 2), the direction of flow of fluid within the feed cylinder 71 will be reversed. In this position of the valve, fluid under pressure passing through the pipe 77 will pass through the control valve 78, through the passage 83 into the cylinder chamber 82 to initiate a movement of the piston 72 toward the left which in turn transmits a motion toward the left of the wheel slide 20 and the grinding wheel 22 to cause an approaching movement of the grinding wheel 22 toward the work piece 17.

The forward end of the valve stem 79 is provided with a spool shaped member 86 which is connected by a pin 87 with a lever 88. The lever 88 is pivotally supported by a stud 89. The lower end of the lever 88 is connected by a stud 90 with link 91 with pull type electric solenoid 92. The valve stem 79 is normally held in its right hand end position (Fig. 2) by means of a tension spring 93 which is connected at one end with the lever 88 and is connected at the other end through a stud 95 which is fixedly mounted relative to the base 10 of the machine. When it is desired to cause an infeeding movement of the grinding wheel 22, the solenoid 92 is energized in a manner to be hereinafter described which serves to rock the lever 88 in a counterclockwise direction (Fig. 2) to shift the valve stem 79 toward the left to initiate an infeeding movement of the grinding wheel 22.

Dash pot

The piston and cylinder mechanism above described serves to cause the grinding wheel 22 rapidly to approach or recede from the work piece 17. In order to reduce the rapid approaching movement to a predetermined grinding feed, it is desirable to provide a wheel feed controlling or regulating mechanism, such as a dash pot mechanism including a pair of dash pot pistons 97 and 98 which may be rendered effective when the grinding wheel 22 is about to engage and contact with the surface of the work to be ground. The dash pot pistons 97

and 98 are normally held in a rearward or right hand end position by means of compression springs. During the rapid approaching movement of the grinding wheel 22, the dash pot pistons 97 and 98 are inoperative.

The piston rod 70 extends toward the rear of the machine. A sleeve 99 is adjustably supported on a piston rod 70 and is provided with a pair of integrally formed diametrically opposed arms 100 and 101 arranged to engage the dash pot pistons 97 and 98, respectively. An adjustable stop collar 103 is adjustably mounted on a threaded portion 104 formed on the rear end of the piston rod 70. When fluid under pressure is admitted into the cylinder chamber 82 to cause the grinding wheel 22 to move toward the work piece 17, the rapid approaching movement continues until the adjustable stop collar 103 engages the end of the sleeve 99. Continued movement of the piston 72 is resisted by the dash pot pistons 97 and 98 which forces fluid under pressure from the dash pot cylinders through an adjustable needle valve 105 into a reservoir 106. By adjustment of the needle valve 105, the exhaust of fluid from the dash pot cylinders may be readily controlled to produce the desired infeeding movement, and the grinding wheel 22 will be moved into the work piece 17 to grind the same at the desired rate of speed. The dash pot mechanism is substantially the same as that shown in the United States patent to R. A. Cole and C. H. Amidon, No. 2,101,790, dated December 7, 1937, and since this feature is not considered to be a part of the present invention, the details of disclosure have not been completely illustrated and described herein. For details of disclosure not contained herein reference may be had to the above mentioned prior patent.

Positive stop

In order to grind a work piece 17 to a predetermined size it is necessary to feed the grinding wheel 22 toward the work piece to grind the same and then to stop the infeeding and allow the grinding wheel 22 to grind out or to allow the sparks to die out in order to round up the work so that it will be ground to a true cylindrical surface of a predetermined size. In the present disclosure, the machine set up is provided with an adjustable stop sleeve 106 which surrounds the sleeve 99. The positive stop sleeve 106 is arranged to engage the end face of the dash pot cylinder head 108 positively to limit the infeeding movement of the wheel slide 20 and the grinding wheel 22.

Multi-stop

It is desirable to provide a multi-stop mechanism for limiting the infeeding movement of the wheel slide 20 so as to limit the infeeding movement of the grinding wheel 22 to facilitate successively grinding a plurality of shouldered portions on the work piece 17 to predetermined sizes. This multi-stop mechanism is preferably arranged so that it may be manually actuated from the operator's station in front of the machine. As illustrated in Fig. 5, a bracket 110 is fixedly mounted on the rear of the machine base and is provided with a downwardly extending portion having a bearing (not shown) which serves as a support for a rock shaft 111. The rock shaft 111 supports a sector-shaped frame 112. The frame 112 serves as a support for a pair of arcuate shaped members 113 and

114 which form an elongated slot or aperture 115 surrounding the threaded portion 104 of the piston rod 70. The arcuate shaped members 113 and 114 are removably mounted on the frame 112 so that they may be readily interchanged if desired. The arcuate shaped members 113 and 114 serve as supports for a plurality of pairs of feed stops or gauge blocks 116, 116a, 117, 117a, 118, 118a, 119, 119a, 120, and 120a which are arranged so that they may be successively swung into operative position between the stop collar 103 and the end of the sleeve 99. The stop blocks or gauge blocks are resiliently supported on the arcuate shaped members 113 and 114. The successive pairs of gauge blocks are interposed between the stop collar 103 and the sleeve 99 to successively stop the infeeding movement of the grinding wheel 20 to produce shouldered cylindrical portions on the work piece 17 of predetermined diameter.

A manually operable mechanism is provided for shifting the frame 112 successively to position the stop or gauge blocks in operative positions, comprising a manually operable lever 125 which is pivotally mounted on the forward end of a stud or shaft 126. The rear end of the stud 126 is supported in the front cover on the base 10 of the machine.

An arm 127 is pivotally supported on the stud 126 and is formed as an integral part of the control lever 125. The lever 127 is connected by a stud 128 to the upper end of a link 129. The lower end of the link 129 is connected by a stud 130 with one end of a lever 131. The lever 131 is fixedly supported on the front end of the rock shaft 111. It will be readily apparent from the foregoing disclosure that when the control lever 125 is rocked in either direction a movement will be imparted through the lever and link mechanism above described to rock the frame 112 so as to position the feed stops successively in operative position.

In order to facilitate positioning the feed stops the upper end of the lever 125 is formed as a pivotally mounted lever 125a which is supported by a stud 132 on the upper end of the lever 125. The lever 125a is provided with a detent 133 which is arranged to engage one of a plurality of notches 134 formed in a bracket 135 which is fixedly mounted on the base 10. The notches 134 are previously numbered so that the operator may visibly know which pair of feed stops are in operative position.

A positioning plate 136 is adjustably mounted on the front edge of the work supporting table 11 and is supported by T-bolts 137 and 138 which anchor the plate 136 relative to the T-slot 52 on the front edge of the table 11. The upper surface of the plate 136 is divided into portions corresponding to the length of the shoulders or portions of the work piece 17 to be ground. These spaces on the plate 136 are numbered to correspond with the shoulder of equal diameter on opposite ends of the work piece 17. It will be readily apparent from the foregoing disclosure that when table 11 is moved longitudinally to position a predetermined shoulder on the work piece 17 in operative position relative to the grinding wheel 22, an index pointer 139 which is fixedly mounted on the bracket 135 will indicate by movement the portion to be ground on the scale formed on the upper surface of the plate 136. The operator may swing the lever 125a to disengage the detent 133 from the notch 134 and may then swing the lever 125 either in

a clockwise or counterclockwise direction so that the detent 133 will engage a notch 134 corresponding to the indication on the scale formed on plate 136 so as to position a predetermined pair of feed stops in an operative position relative to the wheel feeding mechanism.

An electrically operated control mechanism is provided for initiating and controlling the wheel feeding movement of the grinding wheel 22. A control lever 140 is pivotally mounted on a stud 141 which is fixed relative to the base 10 of the machine. The lever 140 is arranged to actuate either one or the other of a pair of push button switches to stop or start the grinding cycle. A push button switch 142 is operatively connected so that when closed it will start an electrical time delay relay 143 in operation which at the same time serves to initiate the solenoid 92 to shift the control valve stem 79 toward the left (Fig. 2) to allow fluid pressure to cause a forward or feeding movement of the wheel slide 20 and the grinding wheel 22. The time delay relay 143 is a standard electrical relay, for example the "Microflex" automatic instantaneous reset timer manufactured by the Eagle Signal Corporation, Moline, Illinois. When the time relay 143 timing interval terminates, the solenoid 92 is deenergized thus releasing the tension of the spring 93 to return the control valve 78 to the position illustrated in Fig. 2. In this position of the valve 78, fluid under pressure will be initiated to cause a rearward movement of the grinding wheel 22 to an inoperative position.

A push button switch 144 serves as a stop switch. When this push button is actuated it serves to break the circuit thus rendering the electrical control inoperative and if actuated during operation serves to return the time relay 143 to its initial starting position and also through the solenoid 92 shifting the control valve 78 to admit fluid under pressure to move the grinding wheel 22 to a rearward or inoperative position. The control lever 140 is arranged so that when it is rocked in a counterclockwise direction (Fig. 2) it will actuate the push button switch 142 to start a grinding cycle. If at any time during the grinding cycle it is necessary or desirable to stop the grinding operation, the control lever 140 may be rocked in a clockwise direction to actuate the push button switch 144 and thus stop the grinding operation.

The operation of this improved shoulder grinding apparatus will be readily apparent from the foregoing disclosure. Assuming all of the adjustments have been previously made, a work piece 17 is placed in position on the work supporting centers 15 and 16. The table 11 is then moved longitudinally to position a predetermined shoulder in operative position with relation to the grinding wheel 22. The operator then notes the index pointer 139 to determine which feed stops should be moved into an operative position. As indicated in Fig. 6, the shoulder member is opposite the grinding wheel 22, according to the

scale on the plate 136. The operator then shifts the control levers 125 and 125a so that the detent 133 is positioned in the notch 134 whose number 3 corresponds with the shoulder to be ground on the work piece 17. The movement of the control lever 125 and 125a serves to shift the corresponding feed stops 118 and 118a into an operative position into the path of the stop collar 103 on the portion 104 of the piston rod 10. After the feed stops have been moved into an operative position the control lever 140 may be shifted in a counterclockwise direction (Fig. 2) to initiate an infeeding grinding cycle. The grinding operation continues for a predetermined time interval after which the electrical time relay 143 breaks the circuit and thus deenergizes the solenoid 92 which allows the control valve 78 to be shifted to cause a rearward movement of the grinding wheel 22 to an inoperative position. The table 11 may then be traversed longitudinally in either direction to position another portion of the work piece 17 with respect to the grinding wheel 22, and the grinding of the plurality of shouldered portions may be continued until all of the shoulders have been ground to the desired predetermined size.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

In a grinding machine having a base, a longitudinally movable work supporting table, a transversely movable grinding wheel slide, a rotatable grinding wheel thereon, means to traverse said table longitudinally, means to feed said slide transversely, means including a plurality of feed stops successively to limit said infeeding movement and successively to grind a plurality of shoulders on a work piece, a pivotally mounted support for said feed stops, an adjustable index bar adjustably supported on said table, and a fixed index pointer on said base cooperating therewith, said index being graduated to correspond with the spaced portions on a work piece, a manually operable pivotally mounted control lever on the front of the base which is operatively connected to move said support successively to position said feed stops into an operative position, and means including a plurality of spaced notches for successively positioning said lever in one of a plurality of positions, said notches being visibly indexed to correspond to the indexing on said bar to facilitate locating a predetermined feed stop in an operative position.

JOHN I. GARSIDE.
